UNITED STATES PATENT OFFICE.

AUGUSTINE W. ESLEECK, OF HOLYOKE, MASSACHUSETTS.

CAR-COUPING.

SPECIFICATION forming part of Letters Patent No. 325,518, dated September 1, 1885.

Application filed July 13, 1885. (No model.)

To all whom it may concern:

Be it known that I, AUGUSTINE W. ESLEECK, a citizen of the United States, residing at Holyoke, in the county of Hampden and State 5 of Massachusetts, have invented certain new and useful Improvements in Car-Couplers; and I do hereby declare the following to be a full, clear, and exact description of the invention, such as will enable others skilled in the art to 10 to which it appertains to make and use the same.

My invention relates to improvements in automatic car-couplers; and it has for its object to provide a coupler which shall be certain in operation, simple in construction, and easily 15 manufactured.

The invention consists in a draw-head formed with the usual bell-mouthing opening for the reception of the coupling-link, and a peculiarly-shaped vertical recess extending from the 20 top of the draw-head to the bottom of said opening, in combination with a right-angularly-bent coupling-pin, one arm of which is secured by a fixed pivotal bolt to the forward end of the draw-head, while its other arm 25 swings in the vertical recess, the shape of which permits sufficient upward movement of the pin to clear the link, but not enough to permit its withdrawal from the recess unless detached at its pivotal point.

Figure 1 of the drawings is a longitudinal sectional view of the draw-head and coupling-link, showing the coupling-pin, which is in elevation, secured by a fixed pivot-bolt in a depression in the top of the draw-head. Fig. 35 2 is also a longitudinal section of the draw-head and coupling-link, the pin in elevation being pivotally secured to the top of the draw-head. Fig. 3 is a perspective view of the coupling-pin.

Referring to the accompanying drawings, A 40 represents the draw-head, in the forward end of which is formed the usual flaring opening, B, for the reception of the coupling-link G.

Extending from the top of the draw-head to 45 the bottom of opening B is a vertical recess, C, the front wall, c, of which is at a right angle to the top surface of the draw-head, while the rear wall, c', has a gradual rearward inclination, thus producing a recess gradually 50 enlarged from the top to its point of intersection with opening B. In the lower wall of

opening B, on a direct line with front wall, c, of recess C, is formed an offset, b, to serve as a support for the end of the vertical arm of the coupling-pin.

D represents the coupling-pin, constructed of a bar of suitable metal, preferably rectangular in cross-section, bent at a right angle, thus forming a horizontal arm, d, and a vertical arm, d'. The lower end of the vertical arm is 60 reduced in thickness on two opposite sides, as shown in Fig. 3, in order to allow it to enter the link; and the horizontal arm at its outer end is perforated, as shown, to receive a pivot-bolt, d''. It is of course evident that the pin, 65 instead of being rectangular in cross-section, may be round or of other desirable shape.

In the top of the draw-head is a depression, E, for the reception of the horizontal arm of the coupling-pin, which is pivotally secured 70 by a fixed pivot-bolt. This depression is just deep enough to allow the upper surface of the pin to lie flush with the top of the draw-head when the pin is down into holding position.

I may, however, dispense with depression 75 E and pivot the horizontal arm of the pin in lugs e on top of the draw-head, as shown in Fig. 2. With this construction it is of course necessary that the vertical arm should be somewhat longer than is required when the horizontal 80 arm is pivoted in the depression.

For the purpose of elevating the pin in the act of uncoupling cars, any of the well-known systems of levers adapted to the purpose may be employed, the pin being provided on top 85 with a ring, F, for attachment thereto of such elevating mechanism.

In operation the link in entering the draw-head strikes against the coupling-pin, moving it backward and upward in the arc of a 90 circle until it is sufficiently elevated to ride over the end of the link, and after passing that it drops by gravity into the link and takes bearing against the bottom of depression E, or top of draw-head, and also against wall c 95 and offset b, thus having support at every possible point, whereby the pivot is relieved of all strain.

The pin, it will be observed, can swing backward and upward but a limited distance before it is arrested by coming into contact with the rear wall of the recess, and it will there-

fore always occupy an operative position, which would not be the case were it subject, by sudden jar, to be thrown clear of the recess. In order to remove the pin from the draw-head, it is only necessary to remove the pivot-bolt.

To guard against any inconvenience which might otherwise possibly arise in case the pin of this coupler should break, I form a hole 10 through the draw-head, as shown in dotted lines, for the reception of an ordinary straight pin.

Having thus described my invention, what I claim as new, and desire to secure by Letters 15 Patent, is—

1. The combination, with a draw-head in which is formed an opening for the reception of the coupling-link and a vertical recess extending from the top of the draw-head to the 20 point of intersection with the rear end of the link-opening, of a right-angularly-bent coupling-pin, one arm of which is secured by a fixed pivot-bolt to the forward end of the draw-head, and the other arm of which occupies and 25 has a limited upward movement in the said recess, substantially as described.

2. A draw-head in which is formed an opening for the reception of the coupling-link, and a vertical recess extending from the top of the 30 draw-head to the point of intersection with the rear end of the link-opening, the front wall of said recess being at a right angle to the top of the draw-head, and the rear wall having a gradual rearward inclination, in combination with a right-angularly-bent coupling- 35 pin, one arm of which is secured by a fixed

pivot-bolt to the forward end of the draw-head, and the other arm of which occupies and has a limited upward movement in the said recess, substantially as described. 40

3. A draw-head in which is formed an opening for the reception of the coupling-link, a vertical recess extending from the top of the draw-head to the point of intersection with the rear end of the link-opening, the front 45 wall of said recess being at a right angle to the top of the draw-head, and the rear wall having a gradual rearward inclination, and an offset in the lower wall of the link-opening on a line with the front wall of the recess, in combination with a right-angularly-bent coupling-pin, one arm of which is secured by a fixed pivot-bolt to the forward end of the draw-head, and the other arm of which occupies and 50 has a limited upward movement in the said recess, substantially as described. 55

4. The combination, with a draw-head formed with a link-opening, B; offset b; vertical recess C, and depression E; of a coupling-pin bent at a right angle, one arm of the pin 60 being secured by a fixed pivot-bolt in the forward end of said depression, and the other arm occupying and having a limited upward movement in the recess, substantially as described. 65

In testimony whereof I affix my signature in presence of two witnesses.

AUGUSTINE W. ESLEECK.
